CLAIM

The ornamental design for a combined perfume bottle and stopper, as shown and described.

DESCRIPTION

FIG. 1 is a front perspective view from above of a combined perfume bottle and stopper showing our new design;

FIG. 2 is a rear perspective view thereof;

FIG. 3 is a front elevational view thereof;

FIG. 4 is a side elevational view taken from the left side of FIG. 3;

FIG. 5 is a side elevational view taken from the right side of FIG. 3;

FIG. 6 is a top plan view of FIG. 3;

FIG. 7 is a bottom plan view of FIG. 3; and,

FIG. 8 is a rear elevational view of FIG. 3.
